UNITED STATES PATENT OFFICE.

JAMES McWILLIAMS, OF JERSEY CITY, NEW JERSEY.

BOILER.

SPECIFICATION forming part of Letters Patent No. 740,304, dated September 29, 1903.

Application filed April 27, 1903. Serial No. 154,469. (No model.)

To all whom it may concern:

Be it known that I, JAMES McWILLIAMS, a citizen of the United States, and a resident of Jersey City, in the county of Hudson and State of New Jersey, have invented a new and Improved Boiler, of which the following is a full, clear, and exact description.

The object of the invention is to provide a new and improved boiler which is simple and durable in construction, comparatively cheap to manufacture, and arranged to insure quick circulation of the water and to produce a large heating-surface in a comparatively small space.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in both views.

Figure 1 is a cross-section of the improvement on the line 1 1 of Fig. 2 arranged as a double furnace-boiler, and Fig. 2 is a longitudinal sectional elevation of the same on the line 2 2 of Fig. 1.

The shell A of the boiler consists, essentially, of front and rear heads A' and A², an approximately semicircular top A³, and a segmental bottom A⁴, having a radius considerably longer than that of the top A³ to form a strong brace for the top, as will be readily understood by reference to Fig. 1.

The bottom A⁴ of the shell A for a double furnace-boiler is connected by water-tubes B B' with side mud-drums C C' and by water-tubes B² B³ with a small mud-drum C², and the said mud-drums C, C', and C² rest on supports D, D', and D², of which the supports D D² sustain a grate E, and the supports D² D' carry a grate E'.

For a single furnace-boiler the middle drum C² and the sets of water-tubes B² B³ are omitted and the single grate extends from the support D to the support D'.

The water-tubes B B' are inclined upwardly and inwardly, while the water-tubes B² B³ are inclined upwardly and outwardly, as plainly shown in Fig. 1, and the said water-tubes

form, with the mud-drums and the grates E E', the fire-box of the boiler.

The sides of the shell A are connected at the junction of the top A³ and bottom A⁴ by casing side plates F F' with the side mud-drums C C', and the forward and rearward ends of the side plates F F' connect with a front head F² and a rear head F³, of which the latter is provided on the inside with a bridge-wall G, having an opening G' directly under the bottom A⁴ of the shell to connect with a connecting or combustion chamber H, establishing connection between the rear end of the fire-box and the rear end of a smoke-return flue I, held in the heads A' and A² and extending lengthwise through the shell A. The forward end of the smoke-return flue I is projected a distance beyond the front head A' to support a smoke-stack J, opening at its lower end into the front end of the smoke-return flue I. The latter is provided at its front end with a suitable door I' for cleaning the smoke-return flue I whenever it is deemed necessary.

In order to strongly sustain the smoke-return flue I within the shell A, a plurality of braces K is employed, preferably in the shape of flat plates set transversely and connected with angle-irons K' and K², of which the angle-irons K' are secured to the under side of the top A³, while the angle-irons K² are secured exteriorly to the top of the smoke-return flue I, as plainly indicated in the drawings. Stay-bolts K³ connect the bottom of the return-flue I with the bottom A⁴ of the shell.

The combustion-chamber H is preferably formed of an inner casing H', covered on the outside by asbestos H², held in place by a covering-plate H³, as plainly indicated in Fig. 2, and the rear or outer wall of the casing H' is preferably perforated, so as to prevent the plate from buckling when subjected to the high heat passing from the fire-box through the combustion-chamber to the return-flue I. The front casing-head F² is provided with suitable doors for giving access to the fire-boxes and also with doors leading to the ash-pits formed below the grates E E' in the usual manner.

Now by reference to Fig. 1 it will be seen that the water-tubes B, B', and B² are ar-

ranged in transverse sets of six or more tubes in depth for each set, and the sets extend throughout the length of the mud-drums, so that the heat generated in the fire-boxes 5 comes in contact with the said tubes B, B', B², and B³ to highly heat the water therein and to insure a quick circulation of the water. It is understood that the innermost tubes of each set are heated to a higher degree 10 than those farther out, and consequently the water will rise in the innermost tubes from the mud-drums C, C', and C² into the shell A and flow back again through the outermost tubes from the shell back into the mud-drums without the use of large return-pipes.

By making the bottom A⁴ comparatively flat it is evident that the upper ends of the tubes B, B', B², and B³ can be readily connected with the bottom A⁴ and securely expanded and beaded in place. It will further be seen that by the arrangement described a very large heating-surface is provided in a comparatively small space, and hence the boiler is very serviceable for use as a marine 25 boiler.

Having thus described my invention, I claim as new and desire to secure by Letters Patent—

1. A boiler, comprising a shell, a return-flue suspended within the shell and having its forward end projecting beyond the front head of the shell and provided with a door therein, three spaced mud-drums extending longitudinally below the shell, grates between the 35 drums, sets of water-tubes inclined upwardly and inwardly and connecting the side mud-drums with the shell, two sets of water-tubes inclined upwardly and outwardly and connecting the center mud-drum with the shell, 40 a chamber connecting the rear end of the fire-box with the rear end of the return-flue, and a smoke-flue supported upon and opening into the forward end of the return-flue, as set forth.

45 2. A boiler comprising a shell, a return-

flue suspended within the shell, spaced mud-drums extending longitudinally below the said shell, a grate between the mud-drums, sets of water-tubes connecting the mud-drums throughout their length with the bottom of the said shell, the said tubes forming with the grate a fire-box, and a connecting-chamber connecting the rear end of the fire-box with the rear end of the return-flue, the said connecting-chamber having a perforated inner wall, a sheet-iron cover and an asbestos filling between the wall and cover, as set forth.

3. A boiler comprising a shell having heads, a top section and a bottom section, a return-flue extending through the shell and held in the said heads, stay-bolts connecting the bottom section of the shell with the bottom of the said return-flue, and braces connecting the upper portion of the top section of the shell with the top of the said return-flue, as set forth.

4. A boiler, comprising a shell having heads, a top and a bottom section, a return-flue suspended in the shell and having its forward end projecting beyond the front head of the shell and provided with a door, a bridge-wall having an opening directly below the bottom section of the shell, mud-drums extending longitudinally below the shell, a grate between the drums, water-tubes connecting the mud-drums with the shell, a combustion-chamber extending from the upper end of the bridge-wall to the rear head of the shell and connecting the fire-box with the return-flue, and a smoke-flue supported upon and opening into the projecting end of the return-flue, as set forth.

In testimony whereof I have signed my name to this specification in the presence of 85 two subscribing witnesses.

JAMES MCWILLIAMS.
